UNITED STATES PATENT OFFICE.

ABRAHAM L. WAGNER, OF NEW YORK, N. Y., ASSIGNOR TO A. L. WAGNER MFG. CO. INC., OF NEW YORK, N. Y.

DESIGN FOR A PERFUME ATOMIZER OR ARTICLE OF SIMILAR NATURE.

Application filed May 21, 1927. Serial No. 22,120. Term of patent 3½ years.

To all whom it may concern:

Be it known that I, ABRAHAM L. WAGNER, a citizen of the United States, residing at New York, in the county and State of New York, have invented a new, original, and ornamental Design for a Perfume Atomizer, or Article of Similar Nature, of which the following is a specification, reference being had to the accompanying drawing, forming a part thereof.

The figure is a prospective view of a perfume atomizer showing my new design.

I claim:

The ornamental design for a perfume atomizer or article of similar nature, as shown.

In testimony whereof I affix my signature.

ABRAHAM L. WAGNER.
